UNITED STATES PATENT OFFICE.

JOHN S. BRENNAN, OF MILWAUKEE, WISCONSIN.

BURNER-DRUM-LIFTER HEAD.

Application filed December 30, 1922. Serial No. 609,936.

To all whom it may concern:

Be it known that I, JOHN S. BRENNAN, a citizen of the United States, and resident of Milwaukee, in the county of Milwaukee and

5 State of Wisconsin, have invented certain new and useful Improvements in Burner-Drum-Lifter Heads; and I do hereby declare that the following is a full, clear, and exact description thereof.

10 This invention relates to burner drum lifting heads and is particularly directed to a device adapted to lift the drums of oil burners.

In oil burners as heretofore constructed, 15 provision has been made for lifting the drums when it is desired to light the wick. However, a great deal of difficulty has been experienced in removing the wicks from burners of this type, as the lifting head interferes with the free manipulation of the 20 operator's fingers, which is required when removing the wick. It is to overcome this defect that the present invention is designed.

Objects of this invention are to provide a 25 burner drum lifting head, so constructed that it will function efficiently as a lifter and also will provide the necessary freedom for the operator's fingers while removing the wick, and to provide a burner drum lifter 30 which is constructed to permit the free passage of air, and which may be produced in an extremely cheap and simple manner.

An embodiment of the invention is shown in the accompanying drawing, in which—

35 Figure 1 is a vertical sectional view thru a burner with the device in position, such view corresponding to a section on the line 1—1 of Figure 2.

Figure 2 is a plan view of the construction shown in Figure 1.

40 Referring more particularly to the drawings, it will be seen that the burner comprises the usual depressed portion 1, within which a wick 2 is seated, and which terminates in an upper peripheral channel 3 adapted to detachably receive the burner drum 4 indicated in dotted lines in Figure 1.

45 A perforated wall 5 extends transversely across the upper portion of the burner proper, and above such wall, a second perforated wall 6 extends across the lower portion of the burner drum 4 and joins the inner walls of such drum, in accordance with the usual practice. The burner drum lifter comprises 50 a vertically movable rod, 7, whose upper

threaded end 8 is screwed into a plate 9. The plate 9 is supported by the rod 7 and the rod may be supported, if desired, in any desired manner.

The plate 9 is adapted to be pushed upwardly by means of the rod 7, and upon engaging the perforated wall 6, is adapted to lift the burner drum upwardly to allow access to be had to the wick. The plate 9 is contoured, as shown in Figure 2, to provide 60 a plurality of upturned tongues 10 of relatively small width. These tongues are regularly spaced a considerable distance apart to provide free and unobstructed spaces therebetween. These spaces not only provide 65 for the free passage of air, but also provide the necessary space to permit the entrance of the operator's fingers when the wick is being removed. In this connection, it is to be noted that the operator grasps the 70 wick by inserting his thumb upon the inner side thereof, and his fingers upon the outer side. It is therefore apparent that it is necessary 75 to provide the spaces, as described above, to permit the free manipulation of 80 the operator's fingers.

It is further to be noted that the peculiar construction of burner drum lifter provides this necessary space, both for the air and for the operator's fingers in an extremely simple and efficient manner, and that the head may be formed very cheaply from stampings 85 without requiring an elaborate series of operations to form the various apertures which are usually provided thru the head to permit free passage of air. Instead of this elaborate construction, a simple cut out is provided, whereby both the freedom for the operator's fingers and for the free flow of 90 air is secured.

95 I claim:—

1. A burner drum lifter comprising a vertical rod, and a plate carried by the upper portion of such rod, said plate having a plurality of recesses cut inwardly from its 100 marginal edge to provide spaces for an operator's fingers.

2. The combination of an oil burner having a wick and a burner drum removably mounted thereabove and provided with a 105 transverse web, and a burner drum lifter comprising a vertical rod and a plate secured to the upper end of such rod and positioned beneath said transverse web, said plate having a plurality of cut-outs extend- 110

ing inwardly from its peripheral margin and adapted to accommodate the operator's fingers when manipulating the wick.

3. The combination of an oil burner having a wick and a burner drum removably mounted thereabove and provided with a transverse web, a burner drum lifter comprising a vertical rod and a plate secured to the upper end of such rod and positioned beneath said transverse web, said plate having a plurality of cut-outs extending inwardly from its peripheral margin and adapted to accommodate the operator's fingers when manipulating the wick, and having a plurality of upturned regularly spaced fingers adapted to engage the said web when said rod is pushed upwardly.

4. The combination of an oil burner having a wick and a burner drum removably mounted thereabove provided with a transverse web, and a burner drum lifter comprising a vertical rod and a plate permanently secured to the upper end of said rod and adapted to normally occupy a position adjacent the said wick, said plate having spaced outwardly projecting upturned fingers free of attachment to each other adjacent their outer ends, whereby a space is

left between the fingers to accommodate the operator's fingers when the burner drum is removed and the plate left in position.

5. The combination of an oil burner having a wick and a burner drum removably mounted thereabove and provided with a transverse web, and a burner drum lifter comprising a vertical rod having a threaded upper end, a plate screwed upon said threaded upper end and adapted to normally occupy a position adjacent the said wick, said plate having spaced upturned outwardly projecting fingers free of attachment to each other adjacent their outer ends, said fingers being adapted to engage the outer portion of said web adjacent said burner drum to provide points of contact at widely spaced places between said plate and said web whereby freedom from tilting of said burner drum is assured, the space between said fingers being adapted to accommodate the operator's fingers when the burner drum is removed and the plate left in position.

I testimony that I claim the foregoing I have hereunto set my hand at Milwaukee, in the county of Milwaukee and State of Wisconsin.

JOHN S. BRENNAN.
